(57) **CLAIM**

The ornamental design for a template for ceiling duct openings as shown and described.

DESCRIPTION

FIG. 1 is a top perspective view of a template for ceiling duct openings, showing our new design.

FIG. 2 is an elevational front edge view thereof.

FIG. 3 is an elevational left side edge view thereof.

FIG. 4 is a top view thereof.

FIG. 5 is a bottom view thereof.

FIG. 6 is a partially folded view thereof; and,

FIG. 7 is a fully folded view thereof.

The broken line portions of the figure drawings are included to show portions of the article that form no part of the claimed design.

1 Claim, 6 Drawing Sheets

FIG. 1

FIG. 2

FIG. 3

FIG. 4

FIG. 5

FIG. 6

FIG. 7
